SPECTACLE FRONT

Harry Weissman, New Hyde Park, N. Y.

Application August 3, 1951, Serial No. 16,130

Term of patent 14 years

(Cl. D57—1)

To all whom it may concern:

Be it known that I, Harry Weissman, a citizen of the United States and resident of New Hyde Park, in the county of Nassau and State of New York, have invented a new, original, and ornamental Design for a Spectacle Front, of which the following is a specification, reference being had to the accompanying drawing, forming part hereof.

Fig. 1 is a top plan view of a spectacle front showing my new design.

Fig. 2 is a front elevational view thereof.

Fig. 3 is a front view on an enlarged scale of one of the end ornaments shown in full lines in Figs. 1 and 2.

Fig. 4 is a front view on an enlarged scale of one-half of the ornamentation shown over the nose bridge of the spectacle front.

The dominant features of the design reside in the portions shown in full lines.

I claim:

The ornamental design for a spectacle front, substantially as shown and described.

HARRY WEISSMAN.
